UNITED STATES PATENT OFFICE

169,461

STOOL

Faby G. Tilley, Winston-Salem, N. C.

Application June 16, 1952, Serial No. 20,214

Term of patent 14 years

(Cl. D15—8)

To all whom it may concern:

Be it known that I, Faby G. Tilley, a citizen of the United States, residing at Winston-Salem, in the county of Forsyth, in the State of North Carolina, have invented a new, original, and ornamental Design for a Stool, of which the following is a specification, reference being had to the accompanying drawing, forming part thereof.

I claim:

The ornamental design for a stool, as shown.
FABY G. TILLEY.
